US00D956229S

(12) **United States Design Patent** (10) Patent No.: **US D956,229 S**
(45) Date of Patent: **** Jun. 28, 2022**

(54) **INTRAVAGINAL DEVICE ASSEMBLY**(71) Applicant: **Renovia Inc.**, Boston, MA (US)(72) Inventors: **Marc D. Beer**, Sudbury, MA (US);
Jose Bohorquez, Boston, MA (US);
Samantha J. Pulliam, Boston, MA (US); **Jessica L. McKinney**, Boston, MA (US)(73) Assignee: **Renovia Inc.**, Boston, MA (US)(***) Term: **15 Years**(21) Appl. No.: **29/754,374**(22) Filed: **Oct. 9, 2020****Related U.S. Application Data**

(63) Continuation of application No. 29/686,273, filed on Apr. 3, 2019, now Pat. No. Des. 898,911.

CLAIM

The ornamental design for an intravaginal device assembly, substantially as shown and described.

DESCRIPTION

FIG. 1 is a front and left side perspective view of an intravaginal device assembly, with the intravaginal device removed from the case for ease of illustration, embodying the claimed design;

FIG. 2 is an enlarged front view of the intravaginal device of FIG. 1;

FIG. 3 is an enlarged rear view of the intravaginal device of FIG. 1;

FIG. 4 is a top view of the intravaginal device of FIG. 1;

FIG. 5 is a bottom view of the intravaginal device of FIG. 1;

FIG. 6 is a right side view of the intravaginal device of FIG. 1;

FIG. 7 is a left side view of the intravaginal device of FIG. 1;

FIG. 8 is a front and left side perspective view of a case, in a closed position, containing the intravaginal device shown in FIG. 1;

FIG. 9 is an exploded view of the case and intravaginal device of FIG. 8;

FIG. 10 is a front and left side perspective view of a partially opened case containing the intravaginal device shown in FIG. 1;

FIG. 11 is an enlarged front view of the case containing the intravaginal device shown in FIG. 8;

FIG. 12 is an enlarged rear view of the case containing the intravaginal device shown in FIG. 8;

FIG. 13 is a right side view of the case and intravaginal device shown in FIG. 10;

FIG. 14 is a left side view of the case and intravaginal device shown in FIG. 10;

FIG. 15 is a top view of the case and intravaginal device shown in FIG. 10; and,

FIG. 16 is a bottom view of the case and intravaginal device shown in FIG. 10.

The broken lines show portions of the intravaginal device assembly that form no part of the claimed design.
